UNITED STATES PATENT OFFICE.

JOHN S. MUCKLÉ, OF PHILADELPHIA, PENNSYLVANIA, ASSIGNOR TO STANDARD ELEVATOR INTERLOCK COMPANY, OF PHILADELPHIA, PENNSYLVANIA, A CORPORATION OF PENNSYLVANIA.

DOOR-LOCKING MECHANISM FOR ELEVATORS.

SPECIFICATION forming part of Letters Patent No. 770,601, dated September 20, 1904.

Application filed July 14, 1903. Serial No. 165,481. (No model.)

To all whom it may concern:

Be it known that I, JOHN S. MUCKLÉ, a citizen of the United States, residing in Philadelphia, Pennsylvania, have invented certain Improvements in Door-Locking Mechanism for Elevators, of which the following is a specification.

The object of my invention is to make a reversible door-lock for the landing-doors of elevators, so that the mechanism can be used either for right or left handed doors. This object I attain in the following manner, reference being had to the accompanying drawings, in which—

15 Figure 1 is a face view of my improved elevator-landing door-locking mechanism. Fig. 2 is a section on the line 2 2, Fig. 1. Fig. 3 is a section on the line 3 3, Fig. 1. Fig. 4 is a perspective view of the spring-lock. Fig. 20 5 is a perspective view of the locking-lever for the plunger carried by the elevator-car, and Fig. 6 is an inverted plan view showing the plunger and locking mechanism in position.

25 A is a plate, preferably made in a single casting, having a central depression *a*, in which rests a spring-actuated locking-lever B. This lever is pivoted to the plate by a pin *b*, passing through lugs *a'* on the plate A, and this lever extends under a strap *a''* at the upper end of the plate, the strap in the present instance being cast integral with the plate.

C is a spring which is coiled around the pivot-pin *b* and extends under the lever B, as shown, so as to force the lever out against the strap *a''*, and when in this position the lever locks the landing-door of the elevator and the door can only be released by operating a plunger S on the car.

30 40 On each side of the plate are orifices *d*, screw-threaded in the present instance and adapted to receive a pivot-pin D. This pin forms the pivot for the lever E, which locks the plunger S on the car to the elevator-well at the landing and prevents the movement of the controlling mechanism on the car when the landing-door is open. This lever has three arms in the present instance, *e e' e''*, the arms *e'* be-

ing a weight for shifting the lever when it is not held in position by the landing-door. The 50 landing-door acts upon the arm *e* and holds it against the stop *i* on the plate A; but as soon as the door is shifted the weight *e''* causes the lever to swing on its pivot and to strike the stop *i*. This brings the arm *e* back of a flange 55 *u* on the plunger S on the car and locks the plunger, preventing the operating mechanism being shifted. It will be noticed in referring to Fig. 5 that the arm *e* of the lever E has two members, so that it can be turned to be used on 60 either the right or left hand side of the plate A. It will therefore be seen by the above-described mechanism that only one set of castings need be carried in stock and the plate can be used on a door opening either at the right 65 or left hand side.

In the inverted view, Fig. 6, I have shown the plate A having a spring-lever in combination with the plunger S, which is carried by the elevator-car. This plunger is adapted 70 to a guide-plate T, secured to the under side of the car, and is actuated through lever mechanism connected to the starting and stopping gearing on the car. Carried by this plunger is a centrally-situated wheel *s*, mounted on the 75 spindle *s'*. This wheel is preferably faced with some yielding material, such as rubber. On each side of the plunger are flanges *u u*, which are so proportioned that they will be engaged by the arm *e* of the three-armed lever E, which 80 can be pivoted on either side of the plunger A. By arranging the plunger with a double flange it can be used either in connection with a right-hand or left-hand opening door.

I claim as my invention—

1. The combination in an elevator-door lock, of a plate, a central door-locking lever pivoted thereto, said plate having an orifice on each side of the center, a pivot-pin fitting either orifice, and a lever for locking the operating mechanism on the car and mounted on the pin, substantially as described. 85

2. The combination in an elevator-door lock, of a plate, a central door-locking lever pivoted thereto, said plate having an orifice on 90 each side of its center, a pivot-pin fitting 95

either orifice, and a locking-lever mounted on the pin and having three arms, one arm being a weight, the second arm being actuated by the door and the third arm locking the mechanism carried by the car so as to lock the operating mechanism when the car is at a landing and the door open, substantially as described.

3. The combination in an elevator-door lock, 10 of a plate secured to the wall of the elevator-well, a lever pivoted to the plate, and an independent spring extending under the lever and arranged to hold it normally away from the plate and in locking position so as to lock 15 the landing-door when closed, substantially as described.

4. The combination of the plate having a central recess, a strap extending over the recess, and lugs, a locking-lever pivoted to the 20 lugs and passing under the strap, and a spring extending under the lever tending to keep it pressed out against the strap, substantially as described.

5. The combination in an elevator-door lock, 25 of a plate, a three-armed locking-lever pivoted to the plate, one arm of said lever being in the path of the door, the other arm being weighted and the third arm arranged to engage mechanism on a car and having two 30 members so that the lever can be used in connection with either a right or left handed door, substantially as described.

6. The combination of a plate having a central recess, a strap extending over the recess 35 at its upper end, and lugs at its lower end, a lever pivoted to the lugs and extending under the strap, a spring for forcing the lever out

against the strap and in the path of the door to be locked, said plate having two orifices one on each side of the center, a pivot-pin 40 fitting either orifice, a three-armed lever arranged to swing on the pivot, one arm being in the path of the landing-door, the other arm being in the form of a weight and the third arm being double and arranged to lock the 45 controlling mechanism on the car, said plate having stops on each side of the center of the plate for controlling the movement of the lever, substantially as described.

7. The combination of the plate secured to 50 the wall of an elevator-well, a spring-lever pivoted to the plate, a locking-lever for the plunger arranged to be mounted on either side of the plate, a car, a plunger carried by the car, and means for actuating the plunger, 55 said plunger having a centrally-located wheel to act upon the spring-lever and having a flange on each side with which the lever hung to the plate can engage when the door is open, substantially as described. 60

8. The combination in an elevator-door lock, of a plate, a door-locking lever, means on the car for actuating said lever, and a locking-lever pivoted to the plate and operated by the door, one arm of said lever having two members so that the lever can be reversed, substantially as described.

In testimony whereof I have signed my name to this specification in the presence of two subscribing witnesses.

JOHN S. MUCKLE.
